Chicago, Ill., a corporation of Illinois

Application April 16, 1956, Serial No. 41,081

Term of patent 14 years

(Cl. D34—5)

Fig. 1.

Fig. 2.

Fig. 1 is a perspective view of a coin-controlled game apparatus showing my new design;

Fig. 2 is a side elevational view thereof as viewed from the side opposite to that shown in Fig. 1.

The back is substantially plain.

A portion of Fig. 1 is diagonally lined to indicate transparency.

The balls shown in broken lines are for illustrative purposes only.

I claim:

The ornamental design for a coin-controlled game apparatus, as shown and described.
